UNITED STATES PATENT OFFICE.

BART LOBEE, OF BUFFALO, NEW YORK.

DUST-SEPARATING TANK.

974,163.

Specification of Letters Patent. Patented Nov. 1, 1910

Application filed April 1, 1909. Serial No. 487,278.

To all whom it may concern:

Be it known that I, BART LOBEE, a citizen of the United States, residing at Buffalo, in the county of Erie and State of New York, have invented certain new and useful Improvements in Dust-Separating Tanks, of which the following is a specification.

My invention relates to improvements in dust separating tanks, or as is sometimes termed, "dust collectors", such as are used in connection with a suction pump or vacuum-inducing apparatus and a pneumatic renovating or cleaning-tool.

My invention has for its object the production of an apparatus by means of which the dust and dirt drawn into it by a suction-pump or vacuum-inducing apparatus is collected therein, and so that the removal of dust and dirt can be accomplished conveniently and with despatch.

It also has for its object the production of a simple and inexpensive apparatus in which all parts are easily accessible for removal or cleaning.

Another object is the provision of suitable means for withdrawing in bulk the coarser particles of dust and dirt collected therein, and to otherwise improve on apparatus of this type.

To these ends my invention consists in the construction, arrangement, and combination of parts to be hereinafter described and particularly pointed out in the appended claims.

In the drawings,—Figure 1 is a vertical longitudinal section of my apparatus showing a portion of the connections to a cleaning or renovating tool and to a suction-pump or vacuum-inducing apparatus. Fig. 2 is a horizontal section taken on line $x-x$, Fig. 1. Fig. 3 is a transverse vertical section taken on line $y-y$, Fig. 1. Fig. 4 is a transverse section taken on line $z-z$, Fig. 1. Fig. 5 is a detached perspective view of the clamp-frame for clamping the canvas sack in position. Fig. 6 is a detached perspective view of a cross bar co-operating with said clamp-frame. Fig. 7 is a detached perspective view of the removable head whereby the interior of the apparatus is rendered accessible.

Referring now to the drawings in detail,

corresponding numerals of reference refer to corresponding parts in the several figures.

The reference numeral 8 designates the shell or casing provided with an inlet 9 in its top wall to which is threaded or otherwise secured a fitting 10 for connection thereto of a flexible or other tube, or tubes 11 having connection with a pneumatic cleaning or renovating tool in the usual manner. I have herein shown two flexible tubes 11, but one or more than two may be used if desired, it being only necessary to change the fitting 10 to accommodate the desired number of tubes. The casing is also provided with an outlet 12, having connected thereto a pipe 13 which leads to a suction-pump or other vacuum-inducing apparatus. Said casing is open at one end and a closure or head 14 is removably held to said open end, it having its edges provided with notches 15 through which swinging bolts 16 pivotally secured between lugs 17 formed on the casing are held. Thumb-nuts 18 are threaded onto said bolts so as to clamp said head or closure tightly against the open end of the casing. Right-angular strengthening-ribs 19 are formed on said head or closure and so arranged that the notches 15 extend through the ends of the same, as best shown in Fig. 7, and a handle 20 arranged centrally on said head or closure provides a convenient means for handling the same.

The casing is provided internally with a bearing flange 21, preferably continuous, and a gasket 22 is held against said bearing-flange. A screening-device or canvas sack 23, or other like or foraminous material preferably in the form of a sack, has its marginal or edge-portion at its open end clamped against said gasket, as at 24, by means of a clamp-plate 25. Said plate is preferably of rectangular form and provided with large openings 26 and a solid center 27. The particular form of clamp-plate herein shown comprises side-bars 28 and cross bars 29 arranged at right-angles to intersect at the center and thus provide the solid center 27 above referred to.

Co-operating with said clamp-plate is a cross-bar 30 having one end thereof behind a lug or ear 31 extending inward from one of

the side walls and its other end fitting into a pocket 32 formed in an extension 33 of the casing; said pocket being of sufficient depth to permit the cross-bar to be moved lengthwise so that the end placed behind the lug or ear 31, will clear the same and permit the cross-bar to be conveniently removed. In placing the cross-bar in position, one end thereof is placed into the pocket 32 until it 10 strikes the inner wall thereof; and when thus positioned, the other end of said bar clears said lug or ear and can be swung into a plane behind the same after which the bar can be moved lengthwise to have said end 15 positioned behind said lug or ear, yet retaining the opposite end in the pocket 32. In order that one end of the bar can be conveniently inserted in the pocket 32 without striking the lug or ear 31, said pocket 20 is made comparatively high, thus permitting the bar to be inclined while inserting the same and thereby bringing its opposite end above the lug or ear until after the first-mentioned end is properly inserted in the 25 pocket 32.

Passing centrally through said bar, is a clamping-screw 34 having preferably a conical end adapted to fit into a corresponding depression 35 formed in the solid center of 30 the clamp-plate. When the end of the clamp-screw is forced against the clamp-plate, the cross-bar 30 is forced against the front wall of the pocket 32 and against the rear face of the lug 31, thus providing a 35 rigid support for said cross-bar so that the clamp-plate may be forced against the edge of the sack with proper pressure to clamp it in position.

Resting upon the bottom of the casing is 40 a dust or dirt-receptacle 36, to which is pivotally secured a vertical screen 37 extending from the top of said receptacle to the top wall of the casing, and if for any reason access is desired to the tank behind said 45 screen, it is only necessary to remove the closure or head 14 and swing the screen 37 into a horizontal position so that it closes the top of the receptacle 36. The dust and dirt drawn into the casing by action of the 50 suction-pump or vacuum-inducing apparatus, strikes the screen 37; the coarser particles unable to pass through the meshes of said screen dropping into the receptacle 36, while the finer particles pass through the 55 screen and are drawn rearward against the rear wall of the canvas sack 23, the air passing through the canvas and leaving the dust behind, which then falls to the bottom of the sack.

60 In order to prevent collapse of the rear end of the sack, a wire frame 38 of any suitable construction is sewed thereto. A fine screen 39 covers the outlet 12 of the cas-

ing so that in the event of the sack becoming torn, the dust will not be drawn into the 65 suction-pump or vacuum-inducing apparatus.

The casing is provided with sight-openings 40 fitted with small panes of glass in an air-tight manner so that the operator can 70 ascertain when the receptacle 36 is filled with dust or dirt.

Having thus described my invention, what I claim is,

1. The combination of a casing having 75 an inlet, an outlet, and a bearing-flange between said inlet and outlet, a gasket held against said bearing-flange, a foraminous sack having its outer marginal portion bearing against said gasket, a clamping-element 80 bearing against the outer marginal portion of said sack, a cross-bar having bearing against opposite walls, and a clamping-screw passing through said cross-bar and acting against said clamping-element. 85

2. The combination of a casing having an inlet, an outlet, and an internal continuous flange located between said inlet and outlet, said casing having also a pocket in one of its walls adjacent said flange and an inwardly projecting ear on the opposite wall, a cross-bar having one end entered in said pocket and its other end bearing against the rear face of said ear, a screening-device held against said flange, a clamp-plate having 95 openings and clamping said screening-device against said flange, and a clamping-screw passing through said cross-bar and having its end impinging against said clamp-plate. 100

3. The combination of a casing having an inlet and an outlet, a removable receptacle in the bottom of said casing having a screen hinged thereto and adapted to be normally positioned between said inlet and outlet and 105 a screening-sack between said outlet and said screen with its open end facing said screen.

4. The combination of a casing having an inlet and an outlet, a screen closing the inner end of said outlet, a screening-device in that portion of the casing adjacent said outlet, a removable receptacle in the bottom of said casing, and an upright screening-device of coarser mesh than the first-mentioned 115 screening-device hinged to said receptacle and located between said first-mentioned screening-device and said inlet and so arranged that the dust and dirt extracted thereby from the air will drop into said 120 receptacle. .

5. The combination of a casing having a removable closure at its front end, an inlet in its top wall and an outlet in its rear end, a screening-device in the rear portion of 125 said casing of comparatively fine mesh, a

dirt receptacle in the front portion of said casing and removable through the front end thereof, and a screen hinged to said receptacle and normally in a vertical position, 5 said screen being of comparatively coarse mesh and located between said first mentioned screening-device and said inlet.

In testimony whereof, I have affixed my signature in the presence of two subscribing witnesses.

BART LOBEE.
